UNITED STATES PATENT OFFICE

HOWELL N. DIXON, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

REMOTE CONTROL APPARATUS

Application filed February 19, 1931. Serial No. 518,916.

My invention relates to apparatus for establishing a route for an object or vehicle, and is particularly adapted for, though not limited to, the establishing of a route for cars

5 or cuts of cars in railway classification yards.

I will describe certain forms of my invention, and will then point out the novel features thereof in claims.

In the accompanying drawings, Fig. 1 is 10 a diagrammatic view of a preferred track layout of a classification yard consisting of eight tracks. Figs. 2^a, 2^b and 2^c, when placed together in the order named, with Fig. 2^a on the left, constitute a diagrammatic view of 15 one form of apparatus embodying my invention when applied to the classification yard shown in Fig. 1. Fig. 3 is a diagrammatic view of a preferred form of apparatus to register the automatic control provided by the 20 apparatus shown in Figs. 2^a, 2^b and 2^c. Fig. 4 is a diagrammatic view of a second form of apparatus that may be used with my invention at registration points located along a route. In the several views, like reference 25 characters designate like parts.

Referring to Fig. 1, there is disclosed by way of illustration, the track layout for a classification yard consisting of eight tracks designated by the reference characters 21 to 30, inclusive, it being understood that my invention is in no way limited to this or to any specific number of tracks, but it is thought that the classification yard shown in the Fig. 1, is sufficient to fully disclose the system embodying my invention. The switches designated by the reference characters 2, 4, 6, 8, 10, 12 and 14 are each to be operated by a power switch machine of any of the several types now in general use. As the operating 40 units and the operating circuits of these switch machines form no part of my invention they are omitted from the figure for the sake of clearness. In this instance the control for the switch machines shown in the drawings is that necessary for an electro-pneumatic machine of the direct acting type which is now used at many places for the operation of the switches of classification yards. While this system of control is applicable to classification yards, irrespective of

whether car retarder equipment is used or not, such retarder equipment forms no part of my invention and is therefore not shown in the figures.

Each switch of my invention is provided 55 preferably with a short detector track circuit. Looking at switch 2 for illustration, the track rails are arranged into a track section by the insulated rail joints *a* after the usual manner in classification yards—that is, one rail only is insulated. The usual track battery is connected across the rails of the section at one end and a track relay designated by the reference character TR plus the numeral 2 corresponding to the switch 2 is 60 connected to the rails at the opposite end of this section. As shown in the Fig. 1, this detector track circuit preferably extends from a few feet in front of the switch points to a point located near the frog rail—that is, 65 the section is made just long enough to insure that a switch cannot be thrown under a car. This requires the section to be not less than the maximum spacing between the trucks of a freight car which for practical purposes in 70 the past has been considered 39 ft. A detector track section is arranged at each switch in a similar manner and is provided with a 75 like track circuit.

In my invention the destination of a car 80 or cut of cars is registered at various points between the hump and the most remote switch of the yard. While such registration may be accomplished in different ways, a preferred 85 form is to use the detector track section located at each switch plus a few additional similar track sections, the number of which will depend on the layout of the track and the minimum space desired between cuts or cars. In the Fig. 1, additional detector track 90 sections are provided at the locations 3, 5, 7, 9, 11 and 13. Each of these additional track sections is insulated in the usual manner and provided with a track circuit consisting of a battery connected across the rails at one end and a track relay TR connected across the rails at the opposite end. As this system requires the clearing of a track circuit between each cut of cars in order to release the registration of the destination of that cut of cars, 95 100

the cuts of cars cannot be spaced less than 39 ft. apart when the registration is accomplished by means of detector track circuits.

In some instances, an armature operated by some one of the track relays is shown in the figures in a location that is not adjacent to the relay. In each such case the armature is given a reference character and directly above the armature is placed the reference character of the relay by which that armature is operated.

Referring to Figs. 2^a, 2^b, and 2^c, there is provided a push button panel PB which is indicated by dotted lines at the extreme left-hand end of Fig. 2^a. On this panel PB, which is located at some central office, there is mounted a push button for each track of the classification yard and in the Fig. 2^a, these push buttons are given a reference character corresponding to the reference character of the track with which the push button is associated. In other words, the push button 21 is associated with the track 21, push button 22 with the track 22 and so on for each of the 8 push buttons and tracks. By the operation of these push buttons, the operator is able to effect the setting up of a route from the hump to the classification track corresponding to the push button operated. These push buttons normally occupy the position as shown in Fig. 2^a and when manually depressed, contact is broken at the upper or front contact and made at the lower or back contact. When not under manual operation, the push buttons return to their normal position.

At each registration point which in Fig. 1 is at each switch and at each track section between the track switches, there is provided a plurality of registering relays. These registering relays are designated in the Figs. 2^a, 2^b, and 2^c by the reference character S with the prefix corresponding to the location and a suffix corresponding to the classification track toward which it directs a car or cut of cars. At each registration point there is provided one of such registering relays for each track towards which a car may be directed from that registration point. Thus the number of registering relays required at the switch 2, which is the first switch below the hump, will be 8 corresponding to the total number of tracks of the classification yard. At the location 4, there will be required four registering relays because a car will pass location 4 for any one of the tracks 21, 22, 23 and 24. At the location 6 there will be required but two registering relays one for each of the tracks 21 and 22. In like manner the number of registering relays provided at each of the other locations of Fig. 1 corresponds to the number of classification tracks towards which a car may be directed from that registration point.

At each registration point there is also

provided one lock-out relay designated by the reference character LO, prefixed by a numeral corresponding to the location, and one slow-releasing track repeater relay designated by the reference character TRP prefixed by a numeral corresponding to the location. Thus for each registration point there is provided a plurality of registering relays, one lock-out relay and one track repeater relay. These relays will be located in housings installed to best accommodate the track layout. As will appear as the specifications progress the relays for each registration point will function in groups, each group of which will consist of one registering relay, the lock-out relay and the track repeater relay.

These registering relays, the lock-out relays and the track repeater relays may be of any of the numerous types known to the art but are here shown in a preferred form which is of the type disclosed in the L. V. Lewis application for Letters Patent in the United States, Serial No. 363,047, filed May 14, 1929, when equipped with continuity transfer contacts—that is, the front contact is arranged to be closed before the mating back contact is opened as the relay is energized. At each location throughout the system, there is provided a source of current, which is not shown in the figures for the sake of clearness, the positive terminal being indicated by the reference character B and the negative terminal by the reference character C.

In describing the control circuits, I shall assume that a car is to pass from the hump to the track 21. The operator pushes the button 21 which closes the circuit to relay 2S21 from positive terminal B through the back contact 15 of push button 21, wire 30, a back contact 31 of the relay 2S21, winding of relay 2S21, a second back contact 32 of relay 2S21, a back contact 33 of the lock-out relay 2LO and to the negative terminal C of the source of current. The energization of relay 2S21 closes a stick circuit that extends from the positive terminal B through a back contact 34 of the track repeater relay 2TRP, winding of the lock-out relay 2LO, front contact 35 of the relay 2S21, winding of relay 2S21, a second front contact 36 and to the negative terminal C. In other words, the energizing of the registering relay 2S21 opens its pick-up circuit at the back contact 31 and closes a stick circuit that includes its two front contacts 35 and 36 and the winding of the lock-out relay 2LO and which circuit is so arranged that the two relays 2LO and 2S21 are retained energized in series. The energizing of relay 2S21 closes its front contact 37 which permits current to flow from the positive terminal B through the contact 37, wire 38, a normally closed contact 39 of a push button 2RB located at the switch 2 and which will be referred to later, a nor-

- 5 mally closed contact 40 of a second push button 2NB also located at switch 2, wire 41, front contact of the armature 42 of track relay 2TR, control magnet 2R of the switch machine for the switch 2, rectifier 43 and to the negative terminal C. The energizing of the control magnet 2R brings about the reversing of the switch 2 of Fig. 1 to direct a car from the hump towards the track 21.
- 10 The energizing of the registering relay 2S21 also closes its front contact 44 to supply current from the positive terminal B through contact 44, wire 45, back contact 46 of a registering relay 3S21 at the location 3, winding 70 of relay 3S21, a second back contact 47 of 75 3S21, back contact 48 of the associated lock-out relay 3LO and to the negative terminal C. As the registering relay 3S21 is energized, its pick-up circuit is opened at the back contact 20 46 and a stick circuit is completed for this relay that extends from the positive terminal B through the back contact 49 of track repeater relay 3TRP, winding of the associated lock-out relay 3LO, front contact 50 of relay 25 3S21, winding of relay 3S21, a second front contact 51 and to the negative terminal C. In other words the registering relay 3S21 is first picked up by current supplied from the location 2 and then stuck energized in series 30 with the associated lock-out relay by current from a local source in exactly the same manner that the registering relay 2S21 is first energized by current supplied through the push button 21 and then stuck energized in 35 series with its associated lock-out relay 2LO. The energizing of the registering relay 3S21 closes the front contact 52 and current flows from the positive terminal B through contact 52 along wire 53 and back contact 54, 40 winding of the registering relay 4S21 at the location 4, a second back contact 55, a back contact 56 of the associated lock-out relay 4LO and to the negative terminal C. As the relay 4S21 becomes energized, its pick-up circuit is opened and its stick circuit is 45 closed so that current flows from the positive terminal B through the back contact 57 of the associated track repeater relay 4TRP, winding of the lock-out relay 4LO, front 50 contact 58, winding of 4S21, a second front contact 59 and to the negative terminal C. Again it is noted that the registering relay 4S21 is first picked up by current from the location to the rear and then retained energized in series with the associated lock-out relay by current supplied at the same location. The closing of the front contact 60 of the registering relay 4S21 directs current from the positive terminal B through contact 55 60, wire 61, normally closed contact 62 of a push button 4RB located at the switch 4, normally closed contact 63 of a push button 4NB, contact 64 of the track relay 4TR, the normal control magnet 4N, rectifier 65 and to the negative terminal C. The energizing of 65 the control magnet 4N positions the switch 4 normal, if the switch is not already in its normal position, to direct a car or cut of cars towards the classification track 21. The energizing of the registering relay 4S21 also 70 closes a front contact 66 to supply current to the registering relay 5S21 located at the registration point 5, the circuit being similar to the circuits already traced in connection with the registering relays 2S21, 3S21 and 4S21. Once the relay 5S21 is energized, its stick circuit which includes the lock-out relay 5LO is closed and these two relays are then retained energized. With the registering relay 5S21 energized to close its front 75 contact 67, current is then supplied from the positive terminal B through the contact 67 to the registering relay 6S21 located at the switch 6, the circuit in this instance being similar to the circuits traced for the registering relays at the proceeding registration points. With the front contact 68 of relay 6S21 closed, current is directed to the normal magnet 6N of the switch machine for the switch 6. The circuit for energizing the 80 normal magnet 6N being similar to that traced for the control magnets at the switch locations 2 and 4. If the switch 6 is not already normal, it will be so positioned by the energizing of its control magnet 6N to 85 direct the car to the classification track 21.
- 90 To sum up the system thus far, a momentary closing of the push button 21 by the operator results in the switches 2, 4 and 6 being properly lined up for a car to move from the hump to the classification track 21, and at each registration point along the route, the lock-out relay and the corresponding registering relay are retained energized to prevent current being supplied to any other 95 registering relay to set up any conflicting route.
- 100 In the event the operator desires to direct a car or cut of cars to the classification yard 22, he presses the push button 22 on his operating panel to close the contact 69. The closing of the contact 69 of the push button 22 permits current to flow from the positive terminal B through the normally closed contact 70 of the push button 21, the now closed 105 contact 69 of push button 22, back contact 71 of the registering relay 2S22, winding of this registering relay, a second back contact 72, wire 73, back contact 33 of the associated lock-out relay 2LO and to the negative terminal 110 C. With the picking up of a registering relay 2S22, its stick circuit is closed and which extends from the positive terminal B through the back contact 34 of the track repeater relay 2TRP, winding of the lock-out relay 2LO, 115 wire 16, front contact 74 of the registering relay 2S22, winding of this relay, front contact 75 and to the negative terminal C. It will be noted that the registering relay 2S22 is first picked up and then retained energized in 120 125 130

series with the associated lock-out relay 2LO in exactly the same manner that the relay 2S21 was operated when the operator selected the push button 21.

8 The energizing of the registering relay 2S22 supplies current from the positive terminal B through its front contacts 76, wire 38 and over the circuit previously traced to the reverse control magnet 2R of the switch machine for the switch 2. The energizing of 10 2R insures that the switch 2 is reversed to direct a car from the hump towards the track 22. The energizing of the relay 2S22 also 15 closes its front contact 78 to permit current to flow from positive terminal B in a circuit leading to the registering relay 3S22 at the location 3, and registering relay 3S22 becomes energized in series with its lock-out relay 3LO in the same manner as has been previously pointed out for other registering 20 relays. The energizing of the relay 3S22 now closes its front contact 79 and current is supplied to the circuit leading to the registering relay 4S22 at the location 4 and that relay becomes energized. As the contact 80 of the 25 relay 4S22 is closed, current is supplied to the normal magnet 4N of the switch machine at the switch 4 over the circuit previously traced and switch 4 is moved to its normal position, if it is not already occupying that position, 30 to direct the car towards the track 22. Again the energizing of the registering relay 4S22 closes the front contact 81 and current is supplied to the registering relay 5S22. In turn 35 the energizing of the registering relay 5S22 supplies current to the registering relay 6S22. As the relay 6S22 becomes energized to close its front contact 82, current is supplied to the reverse control magnet 6R of the switch machine for the switch 6 and the switch 6 is reversed to direct the car to the classification 40 track 22.

A further inspection of the Figs. 2^a, 2^b and 2^c will disclose that the operation of any one 45 of the push buttons on the panel PB will result in the energizing of the registering relay and the lock-out relay at each registration point between the hump and the classification track towards which the particular 50 push button operated directs a car. Also that the energizing of the registering relay at each switch location selects the proper control magnet of the switch machine to properly position the switch to route the car 55 from the hump to the classification track corresponding to the push button operated.

Attention is called to the fact that at the 60 location 2 that the energizing of any one of the registering relays 2S21, 2S22, 2S23, and 2S24 will result in the switch 2 being set reverse as the reverse position of that switch directs a car to any one of the tracks 21, 22, 23 and 24. Likewise the energizing of any one of the registering relays 2S25, 2S26, 65 2S27 and 2S28 results in the switch 2 being

set normal as the normal position of the switch 2 directs a car to any one of the tracks 25, 26, 27 and 28. At location 4 the relays 4S21 and 4S22 position the switch 4 normal and the relays 4S23 and 4S24 position the 70 switch 4 reversed. Again at the location 6 the energizing of relay 6S21 positions switch 6 normal and the energizing of the relay 6S22 positions the switch 6 reversed. The groups of relays at the location 8 control the switch 75 8, in a manner similar to that described for the relays at the location 6, to direct a car to either the track 23 or 24. The intermediate or additional registration points 3 and 5 are provided that cars or cuts of cars may follow 80 each other from the hump to the classification tracks 21 or 22 at closer intervals as will appear as the specification progresses. At the switch location 10 the groups of relays correspond in number to those at the location 85 4. Again at the locations 12 and 14, the groups of relays correspond to those described for the location 6 inasmuch as there are but two diverging routes at each of the locations 12 and 14. In order to simplify 90 the figures, the groups of relays for the locations 11, 12, 13 and 14 have been omitted from the figures as they are duplicates of those shown for the locations 5, 6, 7 and 8, respectively, and it is thought that they would add 95 nothing to the understanding of my invention.

It is apparent from the foregoing description that additional tracks can be added to the lay-out by providing additional push buttons on the control panel to correspond to these additional tracks, and by providing additional registering relays to correspond to the additional routes, and by providing additional registration points with the necessary 100 relays. The new groups of relays and the additional registering relays added to the present groups will all function in a manner similar to those already described and thus the addition of these tracks and apparatus 105 will not depart from the scope of my invention.

I shall now assume that three cars or cuts of cars which I shall call X, Y and Z proceed over the hump and that it is desired to direct these cars into the tracks 21, 22 and 24, respectively. As car X reaches the hump, the operator pushes the button 21 which completes the line up of the group of relays from location 2 to the location 6 in the manner above described setting each switch in turn in a position to direct the car X to the track 21. The energizing of the lockout relay at each location along this route prevents the setting up of the route for any of the following cars until the car X proceeds to each successive location to release the selected group of relays in the manner about to be described. As car X enters upon the track section at the switch 2 and shunts the track relay 2TR, an 110 115 120 125 130

auxiliary power connection is closed through the back contact 83 of the track relay 2TR to the stick circuit of the relays 2LO and 2S21. Also the deenergizing of the track relay 2TR causes the track repeater relay 2TRP to become energized by current flowing from the positive terminal B through the front contact 84 of relay 2LO, back contact 85 of relay 2TR, winding of relay 2TRP and to the negative terminal C. The picking up of relay 2TRP opens the back contact 34, however the relays 2LO and 2S21 are still retained energized by current through the back contact 83. When the car X vacates the track section at the switch location 2, track relay 2TR picks up to open the stick circuit for 2LO and 2S21 at the back contact 83 and also to open the circuit for the repeater relay 2TRP at the back contact 85. As the relay 2TRP is slow-releasing, the relays 2LO and 2S21 become deenergized before the back contact 34 of relay 2TRP is closed and thus the relays at location 2 are restored to their normal condition. As the car X advances past the switch 2, the second car Y is pushed down the hump, and the operator operates the push button 22 to start the lining up of the route from the hump to the track 22 for the second car Y. The closing of the lower contact of the push button 22 energizes the registering relay 2S22 and this relay is then retained energized in series with the lock-out relay 2LO in the same manner as it was energized in series with relay 2S21. However, the routing of the car Y will not immediately proceed beyond the location 2 due to the fact that the route for the car X is still in effect at the location 3. As the car X enters the track section at location 3, the operation of the relays following the shunting of the track relay 3TR is the same as that described for the location 2 when its track relay 2TR was shunted. As the car X vacates the track circuit at the location 3 and the relay 3TR picks up, the lock-out relay 3LO and the registering relay 3S21 are deenergized due to the slow-releasing feature of the track repeater relay 3TRP. As soon as relay 3LO closes its back contact 48 the relay 3S22 is picked up by the circuit closed at the front contact 78 of relay 2S22 and the relays 3S22 and 3LO are retained energized by their stick circuit. As the car X enters and vacates the track circuit of the track section at the location 4, the selected group of relays at location 4 function in the same manner as the relays at the locations 2 and 3 functioned as the car X passed these points, and the route is then at once set up for the following car Y. Likewise at the location 5, the relays function in the same manner as has been previously described, as the car X advances past this point. At the location 6, as soon as the car X passes on into the classification track 21, the registering relay 6S22 is energized and the ener-

gizing of relay 6S22 selects the reverse position of the switch 6 to direct the following car Y into the classification track 22. As soon as the car Y routed for the track 22 leaves the location 2 and the car Z is started down the hump, the operator starts the routing of the car Z by closing the push button 24. This time, as soon as the car Y vacates the track circuit at the location 4, the selecting of the relay 4S24 will cause switch 4 to be reversed to direct the car Z towards the track 24 and as the route of car Y no longer conflicts with the route for the car Z, the setting up of the complete route for the car Z to the track 24 will immediately follow. It is apparent from the foregoing description that the operation of this system permits cars or cuts of cars to follow each other from the hump to the distant classification tracks with a spacing equal to that of the distance between the registration points.

In my system where the control of each route of a plurality of routes is automatically stored in response to the actuating of a push button, that is to the momentary closing of a circuit corresponding to the respective route, the system readily lends itself to the registering in advance of a plurality of routes which are to be successively lined up.

In Fig. 3 is shown a preferred form of apparatus which may be used to register in advance, a plurality of successive routes to be set up for a series of cars or trains. In the Fig. 3 there is shown a registering or storage panel that may be used in connection with the classification yard shown in the Fig. 1. By means of this panel, an operator can take the train sheet of a train to be classified and register the classification track to which each car or cut of cars is designated. Then as the train is pushed over the hump and the cuts of cars detached, the route for each car will be automatically set up in the order registered on the storage panel without any further attention on the part of the operator.

On the panel of Fig. 3, there is provided receptacles of the telephone type. The receptacles being arranged for convenience in horizontal and vertical rows. A horizontal row is provided for each track in the classification yard and a vertical row for each storage desired. In Fig. 3, there is shown eight horizontal rows of receptacles, one for each of the eight tracks of the classification yard of the Fig. 1 and six vertical rows to provide six distinct storages. It will be evident as the description progresses that any number of storages may be provided for by the addition of further vertical rows of receptacles and that additional classification tracks may be provided for by the addition of a corresponding number of horizontal rows of receptacles. In the Fig. 3, the receptacles of each horizontal row are given the reference character corresponding to the

reference character of the track to which this row of receptacles directs cars.

Two relays are provided for each vertical row of receptacles which relays are designated in the Fig. 3 by a reference character consisting of a numeral corresponding to the row with which it is associated plus a prefix A for one relay and a prefix O for the other relay. Also an indicating light is provided for each vertical row of receptacles which is designated in the Fig. 3, by the numeral corresponding to the row plus a suffix A. When the storage panel is used in place of the push button panel PB of the Fig. 2^a, the storage panel circuits indicated by the arrow at the right-hand end of the Fig. 3 are to be connected to the line having the same track numeral shown at the left of the push button panel PB of the Fig. 2^a.

20 One plug is provided for each vertical row of storage receptacles. If the first car or cut of cars listed on the train sheet is designated for the track 24 the operator will insert the plug belonging to the first vertical row of receptacles into receptacle 24 of that row. If the next car or cut of cars is designated for the track 25, the operator will insert the plug belonging to the second vertical row of receptacles into receptacle 25 of that row.

25 30 the third cut of cars is designated for track 21, the operator will insert the plug belonging to the third row into the receptacle 21 of the third vertical row, and likewise one plug will be inserted in each vertical row of receptacles for each cut of cars and this plug will be inserted in the horizontal row corresponding to the track for which that cut of cars is designated. In this instance the maximum number of cuts of cars that can be stored at 40 any one time will be six. However, as stated above any number of such cuts can be arranged for by the addition of more vertical rows of receptacles.

Assuming the above registration has been made for the classification of the three separate cuts of the cars mentioned above, namely the first cut for track 24, the second cut for track 25 and the third for the track 21. As soon as the train advances to the hump, the operator will close the switch AA which will energize the relay A1 over the following circuit; positive terminal B, switch AA, front contact 86 of the track relay 2TR, wire 87, back contact 88 of relay O6, back contact 89 of relay A6, back contact 90 of relay O5, back contact 91 of relay A5 and back contacts 92, 93, 94, 95, 96, 97 and 98 of the relays O4, A4, O3, A3, O2, A2, and O1, respectively, wire 132, winding of relay A1 and to the negative terminal C. It will be noted that as the plug was inserted in the receptacle 24 of the first row, that the lamp 1A was lighted by current flowing from the positive terminal B through the back contact 99 of the relay O6, 65 back contact 100 of the relay A6 and then

through a back contact of each of the relays O5, A5, O4, A4, O3, A3, O2, A2 and O1 in turn, as will be evident from an inspection of the Fig. 3, wire 101, lamp 1A, contact 102 of the receptacle 24 which is closed due to the insertion of the plug, and to the negative terminal C. Likewise the lamp 2A is lighted by current over the same circuit up to the back contact of the relay O2 then along wire 103, lamp 2A, contact 104 of the receptacle 25 and to the negative terminal C. Also the lamp 3A is lighted by a similar circuit as the plug was inserted in the receptacle 21 of the third row to close the contact 105 of that receptacle.

The energizing of the relay A1 closes the front contact 106 and permits current to flow from the positive terminal B through contact 106, the now closed contact 107 of the receptacle 24 of the first row, control wire 108, thence to the corresponding wire 108 of Fig. 2^a and to the relay 2S24 to energize that registering relay in the same manner as was pointed out earlier in the description in connection with the operation of the push buttons. Following the energizing of the relay 2S24, the route is set up for the first cut of cars from the hump to the classification track 24 to which that cut is designated. As the first cut of cars passes down the hump to the location 2 and there shunts the track relay 2TR, the deenergizing of the relay 2TR opens the front contact 86 and closes the back contact 110. However the energizing of the relay A1 closed the front contact 109 and relay A1 is stuck energized by current flowing from the positive terminal B over the same circuit traced for the lamp A1 up to the wire 101 and then from that point through the contact 109, winding of relay A1 and to the negative terminal C. The closing of the back contact 110 of the track relay 2TR supplies current to the relay O1 from the positive terminal B through contact 110, front contact 111 of the relay A1, winding of relay O1, and to the negative terminal C. The energizing of relay O1 opens the back contact 112 in the stick circuit in the relay A1 and also the back contact 98 in the pick-up circuit of relay A1 and that relay thus becomes deenergized. The energizing of relay O1 also opens the circuit to the lamp 1A and extinguishes this light indicating to the operator that this first cut of cars X has passed over the hump and is at location 2. The relay O1 is retained energized after the deenergizing of the relay A1 by a stick circuit that includes its own front contact 113. With contact 113 closed, current flows from the positive terminal B through the circuit that includes the back contact 99 of the relay O6 and a back contact of each of the relays of Fig. 3 in turn up to its own back contact 112 from which point the circuit extends through 120

the front contact 113 to the winding of relay O1 and to the negative terminal C.

As the first cut of cars X vacates the track section at the switch location 2, the track relay 2TR again becomes energized to close its

5 front contact 86 and the circuit by which current was previously supplied to the relay A1 is again closed. This time however the relay O1 is energized and current flowing in th's

10 circuit is supplied through the front contact 114 of relay O1 to the relay A2 and that relay becomes energized. The energizing of relay A2 opens the stick circuit of the relay

15 O1 at back contact 115 to deenergize that relay and at the same time that the back contact 115 is opened the front contact 116 is

20 closed so that the relay A2 is now stuck energized. The energizing of relay A2 supplies current from the positive terminal B

25 through its front contact 117 and the now closed contact 118 of the receptacle 25 of the second row of receptacles, along control wire 119 and thence to the corresponding wire 119 of Fig. 2^a and to the registering relay

30 2S25. The energizing of the registering relay 2S25 is followed by the setting up of the route from the hump to the track 25 in the same manner as would have followed the operation of the push button 25. That is, the

35 energizing of the registering relay 2S25 sets in motion, the setting up of the route for the second cut of cars Y from the hump to the classification track 25 which will take place as fast as the first cut of cars X advances

40 to release the energized relays at the various locations along the route of the car X to the track 24. In this instance, as the route to the track 25 diverges at switch 2 from the route to the track 24 which is the destination

45 of the first cut of cars, the route for the second cut of cars will be at once completed as soon as the first cut vacates the track section at the location 2.

As the second cut of cars Y advances down 45 the hump to the location 2 and shunts track relay 2TR, the closing of the back contact 110 of relay 2TR supplies current through the now closed front contact 120 of the relay A2 to the relay O2 energizing that relay.

50 The energizing of relay O2 opens the stick circuit to the relay A2 at the back contact 121 and at the same time closes its own stick circuit at its front contact 122. Relay A2 now becomes deenergized to open its own stick

55 circuit at contact 116 and the pick-up circuit for the relay O2 at the contact 120. As relay O2 becomes energized, the lamp 2A is extinguished to indicate that the second cut of cars Y has proceeded down the hump to

60 location 2. As this second cut of cars vacates the track section at location 2 and the track relay 2TR again picks up, current is again supplied to the circuit that was traced for energizing the relays A1 and A2. This time

65 however, the relay O2 being energized, the

current is diverted at the front contact 123 to the relay A3 and that relay is energized.

As the relay A3 becomes energized, it opens the stick circuit for the relay O2 at the back contact 124 and closes its own stick circuit

70

at the front contact 125. Front contact 126 of the relay A3 being now closed, current is supplied from the positive terminal B through contact 126, the now closed contact

75

127 of the receptacle 21 of the third row of receptacles and then by the control wire 128 to the corresponding wire 128 of Fig. 2^a and thence to the registering relay 2S21. Relay

80

2S21 is thus energized the same as if the operator had actuated the push button 21 im-

85

mediately after the second cut of cars had vacated the track section at location 2. The selecting of the relay 2S21 sets in motion the setting up of the route for the third cut of

85

cars Z from the hump to the classification track 21. As the route to track 25 for the second cut diverges at switch 2 from the route to the track 21, then the route for the third cut will be at once completed irrespective of

90

the progress of the second cut of cars. How-

95

ever, it will be recalled that the first cut of cars is designated for the track 24 and thus the route for the third cut of cars to the track 21 can be completed only as fast as

100

the first cut of cars advance past the registration points. In like manner the route for any other cut of cars will be automatically set up by the apparatus of Fig. 3 pro-

105

viding a plug has been previously inserted in the proper receptacle. As stated above, the

110

panel disclosed in Fig. 3 only provides for six separate cuts of cars, but it is apparent that a larger number of cuts of cars can be registered by the addition of more vertical

115

rows of receptacles.

The relays A1, O1, A2, O2, A3, O3, etc. therefore constitute a chain of relays oper-

120

ating, as the track relay 2TR becomes alter-

125

nately deenergized and energized, to carry

130

out the control of the routes affected by the

plugs inserted in the various receptacles. In place of operating this chain of relays by the track relay 2TR, they may be operated by means of a push button 131, in the event the switch AB is closed and the switch AA left open.

While in this description, it has been con-

135

sidered that the control is either by means of a manually operated push button panel or by automatic means of a storage panel, it is

140

apparent that both can be provided and the system operated from either.

It becomes obvious from the foregoing de-

145

scription that the different cuts of cars can

plan may be arranged for such registration points as is disclosed in the Fig. 4.

In this case, a light sensitive unit is provided at each registration point. In Fig. 4, two such registration points 3 and 3^a are shown located between the switch 2 and the switch 4 of the Fig. 1. At the locations 3 and 3^a, there is provided light sensitive units U¹ and U², respectively. Each of these units is characterized by a decrease in electrical resistance in respect to increase in intensity of the light to which it is exposed. For example, they may be photo-electric cells and the unit U¹ of location 3 located on one side of the track opposite an electric lamp L¹. These two elements to be so positioned that normally U¹ receives light rays from the lamp L¹ but these light rays are intercepted by the body of the car passing this location. The lamp L¹ is constantly supplied with power from any convenient source such as a transformer T¹. The circuit for the 3TR relay at this location includes a battery 136 and the light unit U¹. The circuit is so adjusted that with U¹ exposed to the light rays of L¹, the current flow is sufficient to retain relay 3TR energized, while when the rays are intercepted by a car, the current is so reduced in value that the armatures controlled by the relay 3aTR drop. At the location 3^a, the lamp L² and the light unit U² are positioned in a manner similar to that described for the location 3 and they control the relay 3aTR in the same manner that the relay 3TR is controlled at the location 3. The relays 3TR and 3aTR can be utilized to control groups of lock out and registering relays in the same manner as the track relays of Figs. 2^a, 2^b and 2^c. By the arrangement of Fig. 4, it is apparent that registration points can be installed as close together as desired and the cuts of cars can follow each other from the hump to the designated classification track at extremely close intervals.

It is sometimes desirable to operate a trimmer engine out of one classification track into another classification track. At each switch location, there is provided two non-stick push buttons for local control of the switch machine at that point. Referring to the switch 2 of the Fig. 2^a, the two push buttons 2NB and 2RB are located at the switch. In the event the switch is aligned in the normal position and it is desired to reverse the switch, a brakeman by holding the push button 2RB depressed will open the automatic control circuits at the contacts 39 and 137 and close a contact 138. With the contact 138 closed then current passes from the positive terminal B through contact 138, wire 41, front contact of the armature 42 of the relay 2TR, reverse magnet 2R, rectifier 43, and to the negative terminal C. The result of the magnet 2R being energized is that the switch 2 is reversed. In a similar manner should the switch 2 be in its reverse position and it is desired to move

it to its normal position, the brakeman by depressing the push button 2NB will disconnect the automatic control circuits and supply current to the normal magnet 2N through the contact 129 with the result that the switch is positioned normal. Similar push buttons are located at each switch of my system.

While in the views here shown my invention is applied to the control of the routes of a railway classification yard it is to be understood that it is equally adaptable to many other locations where a plurality of permissive routes are available for a car or vehicle. Such a system as here disclosed provides a convenient and simple method for establishing a route and for insuring that a route when once established can not be prematurely changed and that the route will be released for use by other cars are rapidly as it is vacated by the first car. When such a system is applied to a classification yard it eliminates the necessity of individual control of each switch by the operator as the car progresses from the hump to the classification track or by a large number of operators each located at the individual switches. Furthermore, the automatic control such as here disclosed permits of a much closer spacing of the respective cuts of cars than is possible to obtain in a system when individual control of each switch is used, while the advantage obtained by being able to register in advance the classification of a complete train will be apparent to all those familiar with this class of work.

Although I have herein shown and described only certain forms of apparatus embodying my invention, it is understood that various changes and modifications may be made therein within the scope of the appended claims without departing from the spirit and scope of my invention.

Having thus described by invention, what I claim is:

1. A control system including, a plurality of routes over which an object may pass, controlling devices located at intervals along each of said routes, a control means for each route located at a central office which when operated selectively governs the controlling devices to establish the route with which said operated control means is associated, means rendered active by the selected controlling devices to retain the established route irrespective of said control means, and means responsive to an object passing over said route to release the selected controlling devices.

2. A control system including, a plurality of routes over which an object can pass, a plurality of registration points located at intervals along each of said routes, a plurality of controlling devices for each registration point one for each route, a control means for each route located at a central office which when operated selects the controlling device

- at each registration point along the respective route to establish the route, lockout means for each registration point rendered active by the selected controlling device to retain the established routes irrespective of the control means, and means responsive to an object passing a registration point to release the selected controlling device and the lockout means at that point. 5
3. A control system including, a plurality of routes over which an object can pass, a registration point included in all of said routes, a registering relay for each route, a control means for each route which when operated selects the registering relay for the respective route to establish the route, a lockout relay rendered active by the selected registering relay to prevent the selecting of a registering relay by any other control means, 10 and means responsive to an object passing the registration point to release the selected registering relay and said lockout relay. 15
4. A control system including, a plurality of routes over which an object can pass, a registration point included in all of said routes, a registering relay for each route, a control means for each route which when operated selects the registering relay for the respective route to establish the route for an 20 object, a lockout relay rendered active by the selected registering relay to prevent the selecting of a registering relay by any other control means, a storage means rendered active by the selected registering relay to retain the established route irrespective of the control means that selected the registering relay, and means responsive to the object passing the registration point to release the selected registering relay and the lockout relay. 25
5. A control system including a plurality of routes over which an object may pass, a plurality of registration points located at intervals along said routes, means located at a central point to select a given route for an object, means located at each registration point along the route selected to prevent a change in the route by the means located at the central office, and means responsive to the object passing a registration point to release the route at that point. 30
6. A control system including, a route over which an object may pass, a plurality of registration points located at intervals along said route, a registering relay for each registration point, manual controlled means to energize the said registering relays to establish the route for the passage of an object, a storage means associated with each registering relay rendered active by the energizing of said registering relay to retain the route set for the object irrespective of said manual controlled means, and means responsive to the object passing a registration point to deenergize the registering relay at that point. 35
7. A control system, including a railway classification yard having a hump and a plurality of classification tracks, means to establish a route from the hump to each of the classification tracks, a plurality of registration points located at intervals along each route, a plurality of registering relays for each registration point, one relay for each route passing the respective registration point; a control means for each route to select the registering relays associated with a given route to establish the route for a car from the hump to the respective classification track, lockout means for each registration point rendered active by the selecting of a registering relay to prevent selecting of a registering relay by the control means of another route, and means responsive to a car passing a registration point to release the lockout means and the registering relay at that point. 40
8. A control system, including a railway classification yard having a plurality of classification tracks, a plurality of track switches each having a normal and a reverse position and capable of arrangement in various combinations as to normal and reverse positions to form a respective route leading to each classification track, a control means for each route located at a central office, means selected by each control means when operated to arrange the switches for the respective route, a lockout means associated with each switch rendered active when the switch is selected for a given route to prevent the switch from being selected by a control means of a different route, and means responsive to a car passing a switch to release the lockout means. 45
9. In combination, a railway switch, a normally deenergized registering relay, a normally deenergized lockout relay, a pick-up circuit for said registering relay; a stick circuit for said registering relay, including the winding of said lockout relay and the winding of said registering relay in series; remote controlled means to control said pick-up circuit, means responsive to traffic passing said railway switch to control said stick circuit, and means controlled jointly by said registering relay and said lockout relay to control the operation of said switch. 50
10. In combination, a railway switch, a plurality of relays each capable of controlling the operation of said railway switch, a lockout relay associated with said plurality of relays, a remotely controlled means to selectively energize one of said plurality of relays together with said lockout relay, and means controlled by said lockout relay when energized to prevent said remote controlled means from selecting any other of said plurality of relays. 55
11. In combination, a railway switch, a control relay, means controlled at a remote point to energize said control relay to select 60

- a given position of the switch, a storage means responsive to the energizing of said control relay to render the remote control means ineffective to control said control relay, and a detector track circuit to deenergize said control relay to release said storage means in response to a car passing over said railway switch. 70
12. In combination, a route along which an object passes, a registering means located at a registration point along the route, a remote control means to govern the registering means to establish the route for an object, a storage means to render said remote control means ineffective to govern said registering means once the route is established, and means including a light sensitive unit to restore the control of said remote control means over said registering means in response to an object passing over said route. 75
13. In combination, a route along which a vehicle passes, a control means located at a controlling point along the route, means located at a remote point to govern said control means to establish the route for a vehicle, a storage means located at said controlling point to prevent the cancelling of said route when once established, and a detector means including a light sensitive unit to release the storage means to restore the control of the means at the remote point in response to the vehicle passing said controlling point. 80
14. In combination, a chain of normally deenergized relays grouped in pairs, a pick-up circuit for energizing the first relay of each pair which circuit includes a back contact of the succeeding relays of the chain and a front contact of the second relay of the preceding pair, a pick-up circuit for energizing the second relay of each pair which includes a front contact of the first relay of the same pair, a stick circuit for each relay including a back contact of each succeeding relay of the chain to retain the relay energized irrespective of its pick-up circuit but which stick circuit is ruptured upon the energizing of the succeeding relay of the chain, means to alternately close the pick-up circuits of the pairs of relays to effect a successive energizing and deenergizing of the relays of the chain, and a traffic control circuit associated with each pair of relays rendered effective by the energizing of the first relay of the pair. 85
15. A control system including, a route over which an object may pass, a plurality of registration points located at intervals along said route to determine the spacing of objects on the route, a registering device for each registration point, manually controlled means to energize the registering devices to set up the route for the passage of an object, lockout means associated with each registering device rendered active by the energizing of said registering device to retain the route 90
- set for the object irrespective of the manual controlled means, and means responsive to the object passing a registration point to release the lockout means to permit the registering device at that point to be energized to set up the route in the rear of the first object for a following object. 95
16. A control system including, a passageway adaptable of arrangement for passing an object from a central point to anyone of a plurality of destinations, registration points located at intervals along said passageway, a registering device for each registration point, a control means at said central point to selectively influence the registering devices to arrange the passageway to direct an object to a given destination, lockout means associated with each registering device effective upon the selecting of its associated registering device to render the control means ineffective to influence the registering device, and means responsive to an object passing a registration point to release the lockout means and permit the control means to influence the registering device for arranging the passageway for a following object. 100
- In testimony whereof I affix my signature.
HOWELL N. DIXON. 105
